UNITED STATES PATENT OFFICE.

ALVAH WASHBURN AND ASA P. MERRITT, OF MEDINA, OHIO.

MACHINE FOR GRINDING SPIDERS.

SPECIFICATION forming part of Letters Patent No. 244,010, dated July 5, 1881.

Application filed October 7, 1880. (No model.)

To all whom it may concern:

Be it known that we, ALVAH WASHBURN and ASA P. MERRITT, of Medina, in the county of Medina and State of Ohio, have invented 5 certain new and useful Improvements in Machines for Grinding Spiders, &c.; and we do hereby declare the following to be a full, clear, and exact description of the invention, such as will enable others skilled in the art to which it 10 pertains to make and use it, reference being had to the accompanying drawings, which form part of this specification.

Our invention relates to a machine for grinding spiders, griddles, and the like; and it consists 15 in certain features of construction and combinations of parts, as will hereinafter be described, and pointed out in the claim.

In the drawings, Figure 1 is an isometric view of our device. Fig. 2 is a detached view, 20 showing the spider and emery-wheel shafts, with the spider and emery-wheel attached, illustrating their operation.

A represents any suitable frame-work or system of standards for carrying the working 25 parts of our machine.

B is the main driving-shaft, to which initial power is applied in any suitable manner.

Upon the shaft B are placed two driving-pulleys, C C'. Instead, however, of the pulleys C C', any suitable gear-connection, if desired, may be substituted.

D is the spider-shaft, having the ordinary groove-and-feather connection with its pulley D', by which it is revolved. The feather-and-groove connection between the pulley D' and the shaft D permits of a longitudinal movement of the shaft through the pulley during revolution. This is a very common expedient in mechanics, and need not be particularly 35 specified. It is sufficient to state that this feather-and-groove connection between the pulley and shaft is the same in the grinding or polishing shaft about to be specified as has already been described for the shaft and pulley D D'.

E is a feeding-handle, and by its manipulation the shaft D is given a longitudinal movement through its bearings upon the frame A.

We do not limit ourselves to any special 50 construction of the manipulating-handle E, or to any method of connecting it with the shaft

D. There are many other familiar methods of connecting these parts, and any method may be adopted that will permit of the free revolution of the shaft, while at the same time such connection should be had between shaft and handle that a longitudinal motion can be given the shaft through its bearings. All that has been specified in relation to this handle and shaft applies to the handle E' and shaft F 55 of the grinder or polisher F'. The shaft F of the grinder or polisher F' is driven by a belt-connection between the pulleys C' and C².

It will be observed that the grinder F' has two faces at an angle to each other, the face f 65 being used for polishing the inside bottom of the spider and the face g for grinding the inside of its rim. The spider S is held in its position upon the mandrel D by any suitable cup-shaped holder, S', or otherwise.

The operation of our device is as follows: The spider S is placed in its holder S' upon the shaft D. The shafts D and F are then brought together until the grinding-face f of the grinder F' impinges against the center of 75 the spider. Meanwhile both the spider and the grinder F' are rotated, the grinder, of course, being revolved the faster. As the parts just named revolve the handles E E' are moved, so that the grinder is made to travel along the 80 bottom of the spider from its center outward toward the rim, as indicated by the dotted lines in Fig. 2 of the drawings. When it reaches the rim of the spider the face g of the grinder will come into operation, as indicated in the 85 dotted lines, to grind or polish the inside of the spider's rim. It will be seen that a single movement suffices to grind the entire interior of the spider, that motion being from the center of the spider outward.

We are aware that polishing and grinding machines have been provided with an adjustable work-holder and an adjustable revolving grinding or polishing wheel; and, further, we are aware that polishing-machines have been 95 furnished with two adjustable polishing-wheels; and hence we would have it understood that we make no claim to such arrangement and construction of parts.

What we claim is—

In a machine for grinding spiders, &c., the combination, with two rotary shafts, located

end to end and at an angle to each other, and mechanism adapted to move one or both of the shafts to and from each other, of a holder secured to the opposing end of one shaft and a 5 grinder secured to the opposing end of the other shaft, said grinder being formed with one inclined face for working against the bottom of the spider or analogous article and another inclined face for working against the rim, sub-
stantially as set forth.

In testimony whereof we have signed our names to this specification in the presence of two subscribing witnesses.

ALVAH WASHBURN.
ASA P. MERRITT.
